PNEUMATIC DISPATCH TUBE APPARATUS

John T. Needham, North Plainfield, and Walter Jacob Mann, Plainfield, N. J., assignors to General Conveyors Limited, Montreal, Quebec, Canada, a corporation of Canada

Application May 11, 1933, Serial No. 670,428

11 Claims. (Cl. 243—19)

This invention relates more particularly to improvements in a dispatch tube terminal structure of the type disclosed in Patent No. 1,972,272, granted Sept. 4, 1934, to John T. Needham. In 5 said terminal structure a housing forms a receiving chamber for carriers and also forms an air conduit between an incoming dispatch tube and an outgoing dispatch tube. The latter tube has a sending terminal within the receiving 10 chamber and the chamber has a door for removal of carriers discharged into the chamber by the incoming tube and for insertion of carriers into said sending terminal.

An important object of the present invention 15 is to provide carrier switch means in such a terminal structure adjustable to permit discharge of carriers into the receiving chamber from the incoming dispatch tube or to direct carriers from said tube to the outgoing tube for transmission 20 to another station.

Other objects of the invention will appear 25 hereinafter.

In the drawings, Fig. 1 is a vertical section approximately on the line 1—1 of Fig. 3;

25 Fig. 2 a horizontal section approximately on the line 2—2 of Fig. 1;

Fig. 3 a front view of the terminal structure; and

Fig. 4 a vertical section on the line 4—4 of 30 Fig. 1.

The terminal structure includes a casing forming a temporary receptacle for carriers delivered to a station by a dispatch tube. Said casing comprises a dome-like upper section 1 and a flat 35 bottom section 2 both approximately rectangular in plan and elongated fore and aft. Preferably the casing sections are metal castings. The section 1 has flat side walls 3 and a wall 4 arched fore and aft and forming the top and 40 ends of the casing. At its lower edge the section 1 is flanged, as at 5, and detachably secured to the bottom section 2 by screws 6 or other fastening means. The sections combine to form a substantially airtight chamber to receive delivered carriers and also form an air conduit between the incoming tube and the out-going tube. At the front of the casing the wall 4 is formed with two doorways 7 and 8 arranged side by side. Through the doorway 7 deposited carriers are 45 removed from the chamber and through the doorway 8 carriers are inserted into a sending terminal within the chamber, as will be explained hereinafter.

Near one of the rear corners of the receiving 50 chamber the bottom plate 2 has an orifice 9 sur-

rounded by a collar 10 formed on the under side of the plate. An incoming dispatch tube 11 has its discharge end fitted in said orifice to discharge carriers upward into the receiving chamber. Near the diagonally opposite front corner of the chamber, the bottom plate has an orifice 12 defined by a collar 13 formed on the under side of the plate and of materially greater depth than the collar 10. At its lower end collar 13 has its internal diameter reduced and an outgoing dispatch tube 14 has its receiving end fitted therein.

Within the receiving chamber there is a tube section 15 of approximately inverted U-form having a curvature approximating that of the arched wall 4. This tube section forms the carrier switch and it is adjustable to permit discharge of carriers from the incoming tube 11 into the receiving chamber or to effect delivery of the carriers from the incoming tube to the outgoing tube 14. At its forward end the switch tube has 20 a swivel connection with the collar 13 holding said end in constant register with the outgoing tube. A short tube section 16 is fitted in the forward end of the switch tube and fixed therein and has its lower end protruding downward and 25 rotatably fitted in the lower end of the collar. The rear end of the switch tube has a flat surrounding flange 17 bearing upon the flat bottom plate 2 and slidably thereon.

Normally, when carriers are to be discharged 30 into the receiving chamber, the switch tube occupies a straight fore-and-aft position in the chamber with its rear end out of register with the discharge end of the delivery tube and blanked by the bottom 2. When, however, the station at 35 which the terminal is located is idle, as at night, and it is desired to route the carriers through to another station the switch is swung laterally about its forward swivel connection to bring its rear end into receiving register with the incoming tube 11. Carriers then pass without interruption from tube 11, through switch tube 15 to tube 14. Mounted on the bottom 2 is a leaf spring 18 having its ends free and formed with locking 40 projections 19. The latter are engageable with a notch 20 in the flange 17 of the switch tube to yieldably lock the tube in either of said adjustments. The switch tube is reached through the doorway 7 for manual adjustment.

At the front of the receiving chamber the switch 50 tube 15 has an entrance orifice 21 opening forward and in constant register with the doorway 8. Carriers are dispatched through the outgoing tube 14 by inserting them through said registering doorway and orifice into the switch tube. The 55

latter thus serves also as a sending terminal and carriers are transmitted by air pressure delivered through the incoming tube 11, by suction in the outgoing tube 14, or both.

5 The doorway 8 through which carriers are inserted for dispatch is closed by a door 22 hinged at its lower edge, as at 23, to lugs 24 formed on the front of casing section 1. Doorway 7 is closed by a similarly mounted door 25. Both doors have 10 leather gaskets 26 which seat against marginal seats around the doorways and seal the receiving chamber substantially airtight. Said door seats incline rearward. Each door has a rotatable latch 27 engageable with the inner margin of the doorway to lock the door closed and said latch is operable by a knob 28 at the front of the door. At 15 its inner face the door 22 bears a guide member 29 partly closing the switch tube orifice when the door is closed. Said member has an arcuate guide face with a curvature corresponding to that of the switch tube and serving to guide carriers through the switch tube past said orifice. Said guide member swings out with the door to a position where it will not obstruct the insertion of 20 carriers. Adjacent its hinges each door has stop lugs 30 engageable with a front structure, to be described hereinafter, to limit outward swinging of the door.

Beneath the door hinges the front of the casing section 1 is formed to define two forwardly opening recesses 31 and 32 located beneath door 22 and door 25 respectively. Within the recess 31 there is an electric switch 33 comprising two normally separated spring contact fingers. At 35 its hinge, door 22 has a cam face 34 engageable with one of said fingers to force it against the other and close the switch when the door is opened. Said switch controls means, not shown, to start a flow of carrier-propelling air through 40 the outgoing tube 14. Recess 32 contains an electric signal lamp 35 to indicate the delivery of carriers into the receiving chamber from the incoming dispatch tube 11.

Within the receiving chamber in advance of 45 the orifice 9 through which the incoming tube discharges, there is a trough-like platform 36 to receive the discharged carriers. Said platform is hinged, as at 37, to one of the side walls of the casing to swing downward. Beneath the platform 50 is an electric switch 38 in circuit with the signal lamp 35. The switch comprises two normally separated spring contact fingers one of which is adapted to be depressed into contact with the other by the platform when the latter is 55 depressed by the weight of a carrier thereon. Thereby the lamp is illuminated to indicate the presence of a carrier in the receiving chamber, to be removed through the doorway 7. The platform has a counterbalance weight 39 to elevate 60 it away from switch 36 when there is no carrier on the platform and thereby permit the switch to open the signal lamp circuit. Between the platform and the delivery orifice 9 there is an 65 upstanding, forwardly, curved baffle 40 to keep carriers on the platform away from the delivery orifice. Carriers discharged into the chamber through said orifice are deflected by the arched wall 4, over said baffle and onto the platform.

At one side of the casing defining the carrier- 70 receiving chamber there is a dispatch tube loop section 41 of approximately inverted U form and having approximately the same curvature as the arched casing wall 4. Joined to the front and rear ends of said loop are dispatch tube sections 75 42 and 43 respectively, forming, together with the

loop, part of another dispatch tube line. Carriers may pass along this line through the station to another station and carriers may also be inserted into the line at the present station for transmission to another station. For insertion 5 of carriers the loop is provided at the front with a sending orifice 44 disposed beside the casing doorway 7. A door 45 closes said orifice and has a hinge mounting on the tube loop similar to the mountings of the aforementioned doors of the 10 casing. It also has similar latching means and a similar stop projection to limit its opening movement. The loop thus serves as a sending terminal and it is provided primarily for relaying carriers taken from the receiving chamber to a 15 station on the separate tube line. The tube loop is preferably a metal casting and, beneath the door hinge it defines a forwardly opening recess 46. A switch 47 similar to switch 33 is mounted in said recess and is operable in a similar manner. 20 by opening the door 45. Switch 47 similarly controls means, not shown, to start a carrier propelling flow of air through the tube section 42, the loop 41 and the tube section 43, for propulsion of a carrier inserted through the orifice 44. 25

At the front of the carrier-receiving casing and the loop 39 there is a frame structure comprising a face plate 48. This plate is rectangular in front view and its lower portion is vertical and extends materially below the level of the receiving casing. Its upper portion recedes to follow the recession of the curved front walls of the casing and the loop 41. Along its upper and side edges the plate extends forward to form a hood 49 over the three doors. Within said hood 30 35 the plate is formed with three apertures which register with the sending orifice of the loop and the two doorways of the casing and are of a size and shape to afford clearance for the doors and their mountings. The plate also has a horizontally elongated aperture in register with the forwardly opening recesses 31, 32 and 46 containing the switch 33, lamp 35 and switch 47 respectively. A forwardly bulging cover plate 50 covers said elongated aperture in the plate and has perforations directly in front of the signal lamp to permit outward passage of rays from the lamp. Said cover plate is fastened to the frame plate by screws. The lower vertical portion of the face plate bears a plurality of carrier-supporting barrels 51 which form a carrier magazine. They extend rearward from the face plate and open forward through it. The face plate is preferably detachably secured to the carrier-receiving casing and to the loop 41, as by screws 52. The entire 40 45 50 55 terminal structure forms a compact unit which is designed for convenient mounting in a compartment of a desk or the like.

Features shown and described in this application but not claimed are claimed in the aforesaid Patent No. 1,972,272.

What we claim is:

1. A terminal device for a pneumatic dispatch system, comprising a housing forming a substantially air-tight carrier-receiving chamber 65 and having a connection for an incoming dispatch tube and a connection for an outgoing dispatch tube, the chamber forming a passage for flow of air from the incoming tube to the outgoing tube; and a switch tube within the 70 chamber mounted for adjustment to permit deposit of carriers into the chamber from the incoming tube and for adjustment to direct carriers from the incoming tube to the outgoing tube and having an orifice in one side thereof for 75

insertion of carriers for dispatch through the outgoing tube, the housing having a door giving access to said orifice for insertion of carriers.

2. A terminal device for a pneumatic dispatch system comprising a casing forming a substantially air-tight carrier-receiving chamber and having a connection for an incoming dispatch tube at the under side of the chamber and a connection for an outgoing dispatch tube at the 10 under side of the chamber, the chamber forming a passage for flow of air from the incoming tube to the outgoing tube; and a switch tube in substantially the form of an inverted U within the chamber and having one end swiveled in 15 constant delivery relation to the outgoing tube connection and adapting the switch tube to be shifted laterally to bring its other end into and out of receiving relation to the incoming tube connection, for directing carriers from the incoming tube to the outgoing tube or permitting the deposit of carriers into the chamber from the incoming tube, said switch tube having an orifice located close to one wall of the casing for insertion of carriers for dispatch through the 20 outgoing tube and said wall of the casing having a door giving access to said orifice for insertion of carriers from outside the casing.

3. A terminal device for a pneumatic dispatch system, comprising a housing forming a substantially air-tight carrier-receiving chamber and having a connection for an incoming dispatch tube and a connection for an outgoing dispatch tube, the chamber forming a passage for flow of air from the incoming tube to the 35 outgoing tube; a switch tube within the chamber mounted for adjustment to permit deposit of carriers into the chamber from the incoming tube and for adjustment to direct carriers from the incoming tube to the outgoing tube and having a side orifice for insertion of carriers for dispatch through the outgoing tube, the housing having a door giving access to said orifice for insertion of carriers; and guide means carried by said door to extend across said orifice when the door is closed to guide carriers in the switch tube past said 40 tube past said orifice.

4. A terminal device for a pneumatic dispatch system comprising a housing forming a substantially air-tight carrier-receiving chamber and 50 having a connection for an incoming dispatch tube and a connection for an outgoing dispatch tube, the chamber forming a passage for flow of air from the incoming tube to the outgoing tube; a substantially U-shaped switch tube within the casing and having one end swiveled in constant delivery relation to the outgoing tube connection and its other end shiftable into and out of receiving relation to the incoming tube connection, for directing carriers from the incoming tube to the outgoing tube or permitting the deposit of carriers into the chamber from the incoming tube, said switch tube having a side orifice for insertion of carriers for dispatch through the outgoing tube and the housing having a door giving access to said dispatch orifice; and a carrier guide carried by said door to extend across said orifice when the door is closed to guide carriers in the switch tube past said orifice.

5. A terminal device for a pneumatic dispatch system comprising a housing forming a substantially air-tight carrier-receiving chamber and having a connection for an incoming dispatch tube and a connection for an outgoing dispatch tube, the chamber forming a passage for flow of

air from the incoming tube to the outgoing tube; a substantially U-shaped switch tube within the chamber and having one end swiveled in constant delivery relation to the outgoing tube connection and its other end adjustable into and out of receiving relation to the incoming tube connection, for directing carriers from the incoming tube to the outgoing tube or permitting the deposit of carriers into the chamber from the incoming tube, said switch tube having an orifice for insertion of carriers for dispatch through the outgoing tube and the housing having a door giving access to said dispatch orifice; and releasable snap locking means to hold the switch tube in either of said adjustments.

6. A terminal device for a pneumatic dispatch system, comprising a housing forming a substantially air-tight carrier-receiving chamber and having a connection at its under side for an incoming dispatch tube and a connection at its 20 under side for an outgoing dispatch tube, the chamber forming a passage for flow of air from the incoming tube to the outgoing tube; a switch tube in substantially the form of an inverted U within the chamber and having one end swiveled in constant delivery relation to the outgoing tube connection and adapting the switch tube to be manually shifted laterally to bring its other end into and out of receiving relation to the incoming tube connection, for directing carriers from the incoming tube to the outgoing tube or permitting the deposit of carriers into the chamber from the incoming tube, the housing having a doorway and the switch tube having a side orifice adjacent said 30 swivel connection and in register with said doorway for insertion of carriers for dispatch through the outgoing tube; a door for said doorway; and carrier guide means carried by said door to extend across said orifice when the door is closed to guide carriers in the switch tube past said 35 orifice, the switch tube being adapted to remain in either of its said positions until manually shifted to the other position.

7. A terminal device for a pneumatic dispatch system, comprising a housing forming a substantially air-tight carrier-receiving chamber and having a connection at its under side for an incoming dispatch tube and a connection at its under side for an outgoing dispatch tube, the chamber forming a passage for flow of air from the incoming tube to the outgoing tube; a switch tube in substantially the form of an inverted U within the chamber and having one end swiveled in constant delivery relation to the outgoing tube connection and adapting the switch tube to be shifted laterally to bring its other end into and out of receiving relation to the incoming tube connection, for directing carriers from the incoming tube to the outgoing tube or permitting the deposit of carriers into the chamber from the incoming tube, the housing having a doorway and the switch tube having a side orifice adjacent said swivel connection and in register with said doorway for insertion of carriers for dispatch through the outgoing tube; a door for said doorway; and carrier guide means carried by said door to extend across said orifice when the door is closed to guide carriers in the switch tube past said orifice.

8. A terminal device for a pneumatic dispatch system comprising a housing forming a substantially air-tight carrier-receiving chamber and having a connection for an incoming dispatch tube and a connection of an outgoing dispatch

tube, said chamber forming a passage for flow of air from the incoming tube to the outgoing tube; a switch tube within said chamber formed with a bend and having one end swivelled in constant 5 delivery relation to the outgoing tube connection and adapting the switch tube to be shifted to bring its other end into and out of receiving relation to the incoming tube connection, for directing carriers from the incoming tube to the 10 outgoing tube or permitting the deposit of carriers into the chamber from the incoming tube, said switch tube having an orifice in one side thereof for insertion of carriers for dispatch through the outgoing tube; and a door affording 15 access for insertion of carriers through said orifice.

9. A terminal device for a pneumatic dispatch system comprising a housing forming a substantially air-tight carrier-receiving chamber 20 and having a connection for an incoming dispatch tube and a connection for an outgoing dispatch tube, said chamber forming a passage for flow of air from the incoming to the out-going tube; a switch tube within said chamber having 25 one end mounted in constant delivery relation to the outgoing tube and its other end shiftable into and out of receiving relation to the incoming tube connection, for directing carriers from the incoming tube to the outgoing tube or permitting the deposit of carriers into the chamber from the incoming 30 tube, said switch tube having an orifice in one side thereof for insertion of carriers for dispatch through the outgoing tube; and a door affording access for insertion of carriers through 35 said orifice.

10. A terminal device for a pneumatic dispatch system, comprising a housing forming a substantially air-tight carrier-receiving chamber and having a connection for an incoming dispatch tube and a connection for an outgoing dispatch tube, the chamber forming a passage for flow of air from the incoming tube to the out- 40

going tube; a switch tube within the chamber mounted for adjustment to permit deposit of carrier into the chamber from the incoming tube and for adjustment to direct carriers from the incoming tube to the outgoing tube and having 5 a side orifice for insertion of carriers for dispatch through the outgoing tube, the housing having a door giving access to said orifice for insertion of carriers; and carrier guide means operable by said door to extend across said orifice when the door is closed to guide carriers in 10 the switch tube past the orifice and to shift away from the orifice by opening of the door for admission of carriers through the orifice.

11. A terminal device for a pneumatic dispatch 15 system comprising a housing forming a substantially air-tight carrier-receiving chamber and having a connection for an incoming dispatch tube and a connection for an outgoing dispatch tube, the chamber forming a passage for flow of 20 air from the incoming tube to the outgoing tube; a substantially U-shaped switch tube within the casing and having one end swiveled in constantly 25 delivery relation to the outgoing tube connection and its other end shiftable into and out of receiving relation to the incoming tube connection, for directing carriers from the incoming tube to the outgoing tube or permitting the deposit of carriers into the chamber from the incoming tube, said switch tube having a side orifice for 30 insertion of carriers for dispatch through the outgoing tube and the housing having a door giving access to said dispatch orifice; and carrier guide means operable by said door to extend across said orifice when the door is closed to 35 guide carriers in the switch tube past the orifice and to shift away from the orifice by opening of the door for admission of carriers through the orifice.
